UNITED STATES PATENT OFFICE.

TURNEY M. WILKINS, OF MILLER, SOUTH DAKOTA, AND AXEL H. REED, OF GLENCOE, MINNESOTA.

ELECTRIC CALL AND VOTING APPARATUS.

SPECIFICATION forming part of Letters Patent No. 429,330, dated June 3, 1890.

Application filed January 16, 1890. Serial No. 337,111. (No model.)

To all whom it may concern:

Be it known that we, TURNEY M. WILKINS and AXEL H. REED, citizens of the United States, residing, respectively, at Miller, in the county of Hand, and State of South Dakota, and Glencoe, in the county of McLeod and State of Minnesota, have invented certain new and useful Improvements in Electric Call and Voting Systems; and we do hereby declare the following to be a full, clear, and exact description of the invention, such as will enable others skilled in the art to which it appertains to make and use the same.

This invention relates to electric call and voting systems; and its object is, in general, first, to provide means whereby the members of legislative assemblies and other similar bodies may individually and silently call a page or other attendant for any purpose required; second, to provide means whereby each member of an assembly may silently announce to the speaker, to the clerk, and to the whole house his vote on any question put by the speaker; and to attain these ends in a practicable and satisfactory manner the object more in detail is, third, to provide means whereby any page or other attendant located in the attendant's room may see at a glance both the location in the assembly-room and the name of the member making a call, so that a new attendant may reply quickly and correctly; fourth, to provide means for removing and replacing the desks of an assembly-room without damage to the electric communicators and yet without any special effort being made to disconnect and reconnect such communicators; fifth, to provide security against misuse of any member's call-buttons in his absence; sixth, to provide means whereby the whole surface of an annunciator-board may be utilized for exposing to view both sides at once of name-cards, and of concealing both sides at once of all the cards, and of exposing any one or more cards at a time independently of the rest; and to this end our invention consists in the construction and combination of parts forming an electric call and voting system, hereinafter described, and particularly pointed out in the claims, reference being had to the accompanying drawings, in which—

Figure I is a plan view of the House of Representatives of the United States Capitol, showing, also, in plan two of our annunciators, which would probably be located in service 55 in a vertical position. Fig. II is a plan view, and Fig. III is a vertical transverse section, of the button-box on the line *x* of Fig. II. Fig. IV is a plan, partly in section, on the line *y* of Fig. V; and Fig. V is a vertical section of 60 a portion of the floor, the foot of a desk-leg, and adjacent parts on the line *z* of Fig. IV. Fig. VI is a face view representing both faces of our annunciator-board, and Fig. VII is an end view of three annunciator-cards. 65

No. 10 represents a desk to be occupied by one member, located, as usual, upon the floor of the assembly-hall.

11 is a button for calling a page or other attendant; 12, a button for voting "yes," and 70 13 a button for voting "no."

14 is a box surrounding the buttons to prevent their being accidentally pressed down, and 15 a hinged lid therefor provided with a lock 16, whereby the whole may be securely 75 closed at pleasure. This box is secured to the desk by screws 30, which are locked inside, so that it cannot be taken off maliciously.

17 represents wires passing from the buttons down the leg 25 of the desk to communicate with other wires 18, which may pass along the floor 26 in grooves or under the floor and up through it again to communicate with the annunciators 19, 20, 21, 22, and 23. The ends of the wires 18 are below the surface of the floor, so as not to interfere with its use for other purposes in the absence of the desks and so as not to be damaged by such use. The wires 17 are each provided with a spring end 24, adapted to project 80 enough below the leg 25 to reach the said ends of the wires 18, and their springs are of sufficient force to crowd away dust and insure electrical contact, the spring ends 24, Figs. I and V, being located so as to register with the 85 ends of wires 18 when the desk is properly located on the floor, which is insured by means of dowels 27, projecting from the desk-legs to register with and engage holes in the floor. These dowels also prevent the weight of the 90 desk resting on the projecting springs 24 when the dowels are out of their holes. 95

- 19 represents an annunciator, which is preferably located against the wall behind the speaker and above his head. This wall being the front of the correspondent's gallery, 5 the annunciator is inclined forward for the double purpose of squaring its front to the line of vision of the assembly below and its back to the line of vision of the reporters above it.
- 10 28 represents the individual cards of the annunciator, each centrally pivoted at its ends and adapted to be turned one-quarter of a revolution on said pivots, whereby its front and rear faces will be exposed when it is in a 15 vertical plane, or at the general slant of the communicator, and whereby its faces will be turned from view when in a horizontal plane, the card being a mere sheet of iron or other material and presenting only its edge to view 20 when in a normal or resting position and provided with a weighted lever 28' to hold it in that position. The lever 28' is an armature, and 32 represents magnets connected with the wires 18, and when a member presses a 25 button it closes a circuit with the wire 18 and vitalizes the said magnet, causing it to attract the armature 28' and to hold the weight elevated and the annunciator-card exposed to view until the magnets 32 are cut out of electric connection, when the weights will fall and restore the cards to a concealed position. On each face of a card the name of a member is printed in letters large enough to be read from any part of the assembly-room. A 30 separate card is devoted to each member's name, and these will be alphabetically arranged, as usual, at the opening of each Congress.

The annunciators are arranged in pairs, 40 one pair 19 facing the front, another pair 20 to the right, and another pair 21 facing to the left, so that they may be readily seen by all the members at their desks. One annunciator of each pair has marked in very large 45 letters above it "Yes" and the other "No," and every member's name is on a similarly-located card in each annunciator. The card of the "yes" annunciator is connected by the wires 18 and 17 with the "Yes" button of that 50 member's desk and the card of the "no" annunciator with the "No" button. When a vote is called for by the Speaker, the votes of the whole assembly might be exhibited within one second to every member of the House. Each 55 member's device being a duplicate of every other's and yet entirely independent thereof, all may vote at once without confusion, or each may vote when he pleases.

22 represents a smaller annunciator, located 60 in front of the clerk and having all the connections before described for his especial convenience in keeping the record and announcing the result of each vote.

The annunciator 23 may be located in an 65 anteroom or other suitable portion of the house to be occupied by the waiting pages and attendants, as it is no longer necessary

that they should be in sight of the members, and their noise and confusion on the floor will thereby be avoided. This annunciator is provided with cards similar to those before described; but the cards are preferably located on a plan corresponding to the plan of the desks on the floor of the house, the integrity of each aisle being maintained on the annunciator, as in the house, to serve as an instant guide to the location of any member making a call. The card bearing each member's name on this annunciator is connected by an electric wire 18 17 with the button marked 80 "Page" on that member's desk, so that the name of the caller and his location are both known at a single glance as well by the green hand as by the experienced ones, and all the confusion of hand-clapping, shouting, and 85 hunting for the caller will be avoided. This annunciator must be provided with a concealing-lever for each card independently of the others, so that when a page starts to answer a call he or the chief page in charge 90 may turn down that call-card. Some of the advantages of this system are as follows: By it, first, a page or attendant may be instantly and silently called; second, the page may see at a glance both the name and location of the 95 caller; third, the votes of the whole assembly may be instantaneously cast and the detailed result of every vote exposed in full view of the assembly and its officers, or each member may vote when he pleases; fourth, time is 100 saved in doing the business of the assembly.

Having thus fully described our invention, what we believe to be new, and desire to secure by Letters Patent, is the following:

1. The combination, in electric voting-machines, of two annunciators, one marked "No" and the other marked "Yes," each having a series of cards marked with the names of members or the numbers of their desks, buttons marked "Yes" and "No" upon each desk, an electric wire for each annunciator, extending to the foot of the desk-leg, an electric wire extending from each button upon the desk down the said leg and having a projecting spring end, the leg being provided with a dowel to engage a hole in the floor, and the "yes" and "no" wires of the annunciators located in the floor in the same relation to the said dowel-holes that the springs of the "yes" and "no" wires of the buttons are to the dowel, substantially as shown and described, whereby the two or more wires of each line will be properly united by the act of placing the desk properly on the floor.

2. The combination of the described "yes" and "no" annunciators, the "yes" and "no" buttons, electric wires connecting them respectively, and passing down a desk-leg having a projecting dowel and separable at the foot of the leg, and that portion of each wire upon the leg having a spring end adapted to engage its mate and extending for that purpose below the leg, the said extension being less than the lengths of the dowel, whereby it

is protected from injury, substantially as shown and described.

3. The combination of a series of desks located in a fixed plan upon a floor and leaving aisles between them, electric call-buttons upon each desk, an annunciator suitably located and having turn-cards located upon it on the fixed plan relative to each other corresponding with the location of the said desks and having spaces between them corresponding with the said aisles, and electric communication between each desk and its corresponding

card on the annunciator, substantially as shown and described, whereby the page may see at a glance the location of the calling-member's desk in the house by the location of the card on the annunciator. 15

In testimony whereof we affix our signatures in presence of two witnesses.
